CONVERSION ARRANGEMENT FOR
SUCTION CLEANERSRalph C. Osborn, Bloomington, Ill., assignor to
Eureka Williams Corporation, Bloomington,
Ill., a corporation of Michigan

Application October 29, 1947, Serial No. 782,815

10 Claims. (CL 15—333)

1 This invention relates to suction cleaners and particularly to a novel and improved converter arrangement therefor.

Suction cleaners of the floor type are particularly adapted for cleaning floor coverings, and it has been the practice heretofore to provide such a cleaner with an arrangement so that attachments may be connected with the cleaner for above-the-floor cleaning operations. Various converter arrangements have been suggested for this purpose heretofore, and while many of them have been quite satisfactory in connection with certain types of floor cleaners, converter arrangements for floor cleaners of the type employing a vertical axis motor with a fan arranged below the motor have not been satisfactory for a number of reasons.

The present invention contemplates a converter arrangement which may be employed in connection with a conventional type of floor cleaner having a vertical axis motor with the fan arranged therebelow and which converter arrangement is easy to use, simple and inexpensive in construction, and which does not require an unconventional design for the suction cleaner.

The principal object of the invention, therefore, is to provide a new and improved converter arrangement for suction cleaners and particularly for a suction cleaner of the floor type having a vertical axis motor with a fan arranged on the under side thereof.

Other and further objects of the invention will be apparent from the following description and claims and will be understood by reference to the accompanying drawings, of which there are three sheets, which, by way of illustration, show preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims. I also contemplate that of the several different features of my invention, certain ones thereof may be advantageously employed in some applications separate and apart from the remainder of the features.

In the drawings:

Fig. 1 is a side elevational view of a floor type cleaner embodying the invention but with the converter disconnected therefrom;

Fig. 2 is an enlarged fragmentary vertical sec-

2 tional view of the cleaner and illustrating the same with the converter connected thereto;

Fig. 3 is a fragmentary sectional view taken along the line 3—3 of Fig. 2;

Fig. 4 is a fragmentary bottom plan view of the suction cleaner showing a part of the nozzle and the communication or air passageway between the nozzle and the air inlet to the fan chamber;

Fig. 5 is a fragmentary sectional view taken 10 along the line 5—5 of Fig. 2;

Fig. 6 is a fragmentary sectional view taken along the line 6—6 of Fig. 2;

Fig. 7 is a fragmentary view similar to Fig. 2 but showing the cleaner with the converter separated therefrom and arranged for on-the-floor cleaning operations; and

Fig. 8 is a fragmentary view similar to Fig. 2 and illustrating a modified form of the invention.

20 A suction cleaner as illustrated in Fig. 1 comprises a body or casing 10 provided with front wheels 12, rear wheels 14, a nozzle 16, a dirt collecting and filtering bag 18, and a handle 20. As shown in Figs. 2, 4 and 7, the nozzle has a downwardly presented mouth, the cleaner body 10 being supported by the wheels 12 and 14 for movement on a surface covering with the nozzle mouth arranged above and presented toward the surface covering. On a hard surface the nozzle mouth is supported by the wheels 12 and 14 a slight distance above the surface, and when the cleaner is arranged on a rug and in operation the mouth of the nozzle will be in engagement with the rug due to the sinkage of the wheels 12 and 14 or the lifting of the rug by the suction of the nozzle, or both.

The cleaner further includes a vertical axis electric motor 22 arranged above a fan chamber 24, the fan chamber being provided with an 30 air inlet 26 which is in communication with the interior of the nozzle 16 by means of the passageway or communication 28. The shaft 23 of the motor 22 projects downwardly through the fan chamber 24 and through the inlet 26 thereof into the communication 28. A fan 30 is operatively arranged in the fan-chamber 24 so as to be driven by the motor 22 during operation thereof and the fan is operative to induce a flow of air into the cleaner through the nozzle mouth, thence through 40 the passage into the fan chamber, and thence through the discharge outlet (not shown) into the dirt collecting and filtering bag 18 where the dirt is separated from the air which circulates through the cleaner.

50 55 A rotary agitator or brush 32 is rotatably ar-

ranged inside the nozzle 16 and is provided with beating or sweeping elements 34 in the form of brushes which upon rotation of the brush 32 are adapted to beat and/or sweep the surface covering presented to the nozzle mouth. A flexible and elastic belt 36 driven by a pulley on the end of the shaft 23 is connected to the brush 32 so as to rotate the same about its axis during operation of the motor and fan, whereby the dirt dislodged from the rug or surface covering will be carried by the air which circulates through the cleaner into the bag 18.

A belt guard 40 spans the nozzle mouth 16 below that portion of the belt which extends around the rotary brush 32. The belt guard comprises a bar, one end of which is pivoted by pin 42 to the arms 44 of a bracket 46 which is mounted inside the nozzle on the front wall thereof by screws 48. Coil springs 50 secured by means of the screws 48 are connected to opposite sides of the belt guard 40 so as to bias the same to the position shown in full lines in Figs. 2 and 7. The aforesaid arrangement, however, permits the belt guard to pivot in a clockwise direction about the pin 42 so as to move to a non-obstructing position relative to the nozzle mouth so as to permit the removal and insertion of the rotary brush 32. The belt guard 40 serves to prevent the rug or parts thereof from becoming caught between the belt and the rotary brush.

The cleaner body 10 is provided with an upwardly facing converter port 52 at the front of the cleaner and approximately midway between the sides thereof, the port 52 communicating with the passage 28 as clearly shown in Figs. 6 and 7. During on-the-floor cleaning operations the port 52 is closed by a cover 54 which is pivotally secured to the cleaner at 56. A coil spring 58 biases the cover 54 to its closed position.

The converter port 52 is adapted to have inserted therein a converter or coupling element 60, the converter 60 having a sliding fit in the port 52 and conforming closely to the shape thereof. The inserted end 62 of the converter is notched or cut away as indicated at 64 so as to permit the converter to be seated in the port 52 as shown in Fig. 2 without the necessity of disconnecting and removing the belt 36, the notch 64 accommodating the strands of the belt 36 as shown in Fig. 3. The side of the inserted end 62 of the converter exposed to the downstream side of the passageway 28 is also cut away as indicated at 66 so as to accommodate the strands of the belt and also to permit the flow of air and dirt entrained therein from the interior of the converter into the passage 28 and the fan chamber.

The other or outer end of the converter 60 is enlarged to form a socket 70 or coupling member for receiving one end of a coupling member 72 on one end of a flexible hose, to the other end of which various suction cleaning tools may be connected. The socket 70 includes a plurality of latches 74 for detachably securing the coupling member 72 therein. The construction of the coupling may be like that disclosed in my co-pending application Serial No. 676,986, filed June 15, 1946, now Patent Number 2,487,470 issued November 8, 1949. With this arrangement, when the converter is assembled with the cleaner the latter may be pulled around on the floor, being supported at such time by the rear wheels 14 and the belt guard 40.

A lever 80 pivoted by the pin 42 to the bracket 46 has an end 82 thereof which projects through a slot 83 into the converter port 52. The belt

guard 40 has an upstanding portion 84 which is arranged inside the lever 80. The converter 60 includes a slide or actuator 86 which is slidably secured to the outside thereof by means of shouldered pins 88. From Fig. 6 it will be observed that the converter port 52 is notched at one side thereof as indicated at 90 to accommodate the slide 86. When the converter 60 is inserted and seated in the port 52, as illustrated in Fig. 2, the end 82 of the lever 80 is in the path of the slide 86 so that when the slide 86 is moved from its position as shown in full lines in Figs. 2 and 3 to that shown in dotted lines in such figures, the lower end 92 of the slide will engage the end 82 and shift the lever from the position shown in full lines to that shown in dotted lines in Fig. 2, thereby pivoting the lever 80 and the belt guard 40 about their pivot 42.

The upper end of the slide is provided with a rest or surface 96 arranged to be engaged by the thumb of a person so that the slide may be shifted as just described so as to shift the belt guard 40 to the position shown in dotted lines in Fig. 2. This will have the effect of raising the nozzle and the front wheels 12 above the surface on which the cleaner is supported and so that the mouth of the nozzle 16 and the rotary brush 32 will be out of operative relation with the surface covering below the cleaner. At the same time the converter 60 will effectively shut off the flow of air from the nozzle to the fan chamber thereby discontinuing the flow of air into the cleaner through the mouth of the nozzle 16. The inserted end of the converter 60 obstructs the passageway 28 as illustrated in Figs. 2, 3 and 4, except for the accommodation for the strands of the belt 36.

When the converter is arranged as illustrated in Fig. 2, air will flow into the passageway through the converter 60 and the cleaner will at such times be arranged for off-the-floor cleaning operations.

The heads of the pins 88 may be arranged on the inside of the converter 60 and the pins extend through holes in the converter wall and through slots 100 and 102 in the slide 86. Washers 104 secured on the outer ends of the pins 88 secure the slide to the converter 60. The slot 100 is provided with an offset 106 which permits the slide to be arranged as shown in dotted lines and with a laterally extending arm 108 hooked under a ledge 110 formed inside the converter port so as to lock the converter 60 to the cleaner. When the rest 96 is pressed downwardly, the downward thrust thereon will normally tend to cause the offset portion 106 of the slot 100 to seat around the pin 88. When it is desired to release the converter from the cleaner, by lifting on the rest 96 and shifting the same laterally the arm 108 may be disengaged from the ledge 110 and the converter pulled out of the port 52. A detent 112 is arranged between the offset 106 and the main part of the slot 100 so as to prevent the accidental shifting of the slide 86.

In addition, the converter may be provided with a latch 114 which is arranged to be engaged by an edge 116 of the cover for holding the converter 60 in its inserted position. By moving the swinging end of the cover 54 away from the converter the latch 114 will be freed so as to permit the converter to be separated from the cleaner. When the converter 60 is pulled out of the port 52 the springs 50 will restore the lever 80 and the belt guard 40 to their normal positions as shown in full lines in Fig. 2. Since the belt

75

guard 40 is movable relative to the lever 30, it will be appreciated that the belt guard 40 may be shifted to a non-obstructing position relative to the nozzle mouth independently of movement of the lever 30.

In the modification shown in Fig. 8 the construction of the cleaner and the converter is the same as that just described except in the following particular. The slide 185 corresponding generally in construction and function with the slide 86 and secured to the converter in the same manner, is extended beyond the outer end of the converter and provided with a rest 196 which extends over an edge of the converter defining the socket 70 and so as to be actuated by a shoulder on the coupling 72 when the same is inserted in the socket 70. In this way the belt guard 40 will be actuated to elevate the front end of the cleaner by the insertion of the coupling member 72 into the socket in the end of the converter 69. In all other respects the construction and operation of the embodiment illustrated in Fig. 8 is the same as that previously described.

While I have illustrated and described preferred embodiments of my invention, it is understood that these are capable of modification and I therefore do not wish to be limited to the precise details set forth but desire to avail myself of such changes and alterations as fall within the purview of the following claims.

I claim:

1. In a suction cleaner having a rug nozzle and arranged for movement on a surface covering with said nozzle in operative relation with respect to said surface covering, a fan provided with an air inlet, means forming an air communication between said nozzle and fan inlet, a motor for driving said fan and having a shaft extending through said inlet into said communication, an agitator associated with said nozzle, a belt extending through said communication and connected to said agitator and shaft for driving said agitator during operation of said motor, a belt guard movably mounted on said cleaner and normally positioned to span said nozzle below said belt, said communication being provided with a converter port, a hollow air conducting converter insertable in said port so as to provide for circulation of air through said converter into said communication and to substantially shut off the flow of air from said nozzle to said fan inlet, a belt guard actuating member movably mounted on said converter and operable when said converter is arranged in said port to shift said belt guard to a position for supporting said nozzle and agitator out of operative relation with said surface covering, said belt guard having a part connected thereto which is arranged to be actuated by said belt guard actuating member.

2. A suction cleaner construction according to claim 1 wherein said agitator comprises a rotary brush arranged in said nozzle and wherein said belt guard is movable to a non-obstructing position relative to said nozzle to permit the removal of said brush therefrom.

3. In a suction cleaner having a rug nozzle and arranged for movement on a surface covering with said nozzle in operative relation with respect to said surface covering, a fan provided with an air inlet, means forming an air communication between said nozzle and fan inlet, a motor for driving said fan and having a shaft extending through said inlet into said communication, an agitator in said nozzle, a belt extending through said communication and connected to said

agitator and shaft for driving said agitator during operation of said motor, a belt guard pivotally mounted on said nozzle and normally spanning said nozzle below said belt, said communication being provided with a converter port, a hollow air conducting converter insertable in said port so as to provide for circulation of air through said converter into said communication and to substantially shut off the flow of air from said nozzle to said fan inlet, a belt guard actuating member on said converter operable to actuate said belt guard to a position for supporting said nozzle and agitator out of operative relation with said surface covering, said belt guard having a part connected thereto which is arranged to be actuated by said belt guard actuating member.

4. In a suction cleaner having a rug nozzle and arranged for movement on a surface covering with said nozzle in operative relation with respect to said surface covering, a fan provided with an air inlet, means forming an air communication between said nozzle and fan inlet, a motor for driving said fan and having a shaft, an agitator in said nozzle, a belt connected to said agitator and shaft for driving said agitator during operation of said motor, a belt guard pivotally mounted on said cleaner and normally spanning said nozzle below said belt, said communication being provided with a converter port, a hollow air conducting converter insertable in said port so as to provide for circulation of air through said converter into said communication and to substantially shut off the flow of air from said nozzle to said fan inlet, and a belt guard actuating member on said converter and operable to actuate said belt guard to a position for supporting said nozzle and agitator out of operative relation with said surface covering.

5. In a suction cleaner having a rug nozzle and arranged for movement on a surface covering with said nozzle in operative relation with respect to said surface covering, a fan provided with an air inlet, means forming an air communication between said nozzle and fan inlet, a motor for driving said fan and having a shaft extending through said inlet into said communication, an agitator in said nozzle, a belt extending through said communication and connected to said agitator and shaft for driving said agitator during operation of said motor, a belt guard pivotally mounted on said cleaner and spanning said nozzle below said belt, said communication being provided with a converter port, a hollow air conducting converter insertable in said port so as to provide for circulation of air through said converter into said communication and to substantially shut off the flow of air from said nozzle to said fan inlet, a belt guard actuating member movably mounted on said converter and operable when said converter is arranged in said port to shift said belt guard to a position for supporting said nozzle and agitator out of operative relation with said surface covering, said belt guard having a part connected thereto which is arranged to be actuated by said belt guard actuating member.

6. In a suction cleaner having a rug nozzle and arranged for movement on a surface covering with said nozzle in operative relation with respect to said surface covering, a fan provided with an air inlet, means forming an air communication between said nozzle and fan inlet, a motor for driving said fan and having a shaft extending through said inlet into said communication, an agitator in said nozzle, a belt extending through

said communication and connected to said agitator and shaft for driving said agitator during operation of said motor, a belt guard pivotally mounted on said cleaner and spanning said nozzle below said belt, said communication being provided with a converter port, a hollow air conducting converter insertable in said port so as to provide for circulation of air through said converter into said communication and to substantially shut off the flow of air from said nozzle to said fan inlet, a belt guard actuating member movably mounted on said converter, said converter being provided with a coupling socket, a coupling member insertable in said socket, said belt guard actuating member being positioned to be engaged and actuated by said coupling member upon insertion thereof into said socket when said converter is arranged in said port, and operable thereby to actuate said belt guard to a position for supporting said nozzle and agitator out of operative relation with said surface covering, said belt guard having a part connected thereto which is arranged to be actuated by said belt guard actuating member.

7. In combination with a suction cleaner having a rug nozzle and supported for movement on a surface covering with said nozzle in operative position with respect to said surface covering, a fan operable for inducing a flow of air into said nozzle, an agitator associated with said nozzle, a motor for driving said fan, a converter port communicating with said nozzle and said fan, a converter insertable into said port so as to establish a flow of air by said fan into said cleaner through said converter and to substantially shut off the flow of air into said nozzle, means carried by said cleaner and operable to elevate said nozzle out of operative relation with said surface covering, an actuator for said means carried by said converter, said converter having a socket, a coupling member insertable in said socket, said actuator being positioned to be engaged and actuated by said coupling upon insertion thereof into said socket.

8. In combination with a suction cleaner having a rug nozzle and supported for movement on a surface covering with said nozzle in operative position with respect to said surface covering, an agitator in said nozzle, a belt for driving said agitator, a motor, a fan driven by said motor and operable for inducing a flow of air into said nozzle and for driving said belt, a converter port communicating with said nozzle and said fan, a converter insertable into said port so as to establish

a flow of air by said fan into said cleaner through said converter and to substantially shut off the flow of air into said nozzle, a belt guard movably mounted on said cleaner and normally positioned to span said nozzle, and operable to elevate said nozzle out of operative relation with said surface covering, and an actuator on said converter for shifting said belt guard and for locking said converter in said converter port.

10. In a suction cleaner having a rug nozzle and supported for movement on a surface covering with said nozzle in operative position with respect to said surface covering, a belt, an agitator driven by said belt and arranged within said nozzle, a fan operable for inducing a flow of air into said nozzle, a motor for driving said fan and said belt, a belt guard pivotally secured to said nozzle and normally spanning said nozzle below said belt, said belt guard being movable to elevate said nozzle and agitator out of operative relation with said surface covering, said cleaner being provided with a communication between said nozzle and said fan and through which said belt extends, said communication being provided with a converter port, a converter insertable in said port and including provisions by means of which suction cleaning tools may be attached to said cleaner by said converter, said converter having means mounted thereon and insertable therewith through said port into said communication for actuating said belt guard to elevate said nozzle and agitator out of operative relation with said surface covering.

15. A suction cleaner construction according to claim 1 wherein said belt guard actuating member is provided with a portion projecting away from said converter and adapted to be engaged by the finger of an operator so that such belt guard actuating member may be moved.

RALPH C. OSBORN.
